UNITED STATES PATENT OFFICE.

JAMES F. BARRY, OF DALLAS, TEXAS, ASSIGNOR TO RIVAL SAFETY RAZOR CORPORATION, A CORPORATION OF THE DISTRICT OF COLUMBIA.

PROCESS OF MANUFACTURING SAFETY-RAZOR BLADES.

Application filed March 21, 1923. Serial No. 626,549.

To all whom it may concern:

Be it known that I, JAMES F. BARRY, a citizen of the United States, residing at Dallas, in the county of Dallas and State of 5 Texas, have invented certain new and useful Improvements in Processes of Manufacturing Safety-Razor Blades, of which the following is a specification.

This invention relates to new and improved methods or processes of manufacturing safety razor blades, and more particularly to the process where a plurality of safety razor blades are manufactured from a strip or ribbon of steel.

15 An object of the invention is to provide a suitable process whereby a plurality of safety razor blades may be manufactured from a ribbon or strip of steel, and the same may be tempered while the blades are in 20 strip form.

Another object of the invention is to provide a process of manufacturing a plurality of safety razor blades from a strip or ribbon of steel, and tempering, polishing, 25 grinding, honing and stropping the same while they are still in strip form.

A further object of the invention is to provide a new and improved process for manufacturing safety razor blades from a strip 30 or ribbon of steel, and after the same have been completed, to break the separate blades off from the strip by means of dies, stamp presses or by hand.

Other objects will appear as the description proceeds.

In the accompanying drawings which form a part of my application,

Figure 1 is a plan view of a strip or ribbon of steel from which the blades are manufactured;

Figure 2 is a plan view of the strip or ribbon of steel after the same has been punched, and

45 Figure 3 is a plan view of the complete safety razor blade, after the same has been broken off from the strip.

Like characters of reference are used throughout the following specification and the accompanying drawings to designate 50 corresponding parts.

The main object of the invention is to provide a process of manufacturing safety razor blades from a strip or ribbon of steel, whereby the several steps of the process may 55 be completed without the use of any special

machinery. In most of the machines used for the manufacture of safety razor blades, there is a complicated set of machinery required, and it is for the purpose of doing away with this expensive machinery, that 60 I have invented my process for manufacturing safety razor blades in strip form.

A strip of steel 1, is first punched in one operation to form the central openings 2 and the end positioning seats or notches 3 65 in the several blades. The seats 3 are adapted to seat over suitable lugs at the ends of the razor to position the blades. It may be desired to also punch out the triangular shape portions 4, shown in dotted lines in 70 the drawings and to leave the blades only connected where the pointed ears or lugs 5 meet, at the opposite sides of the end notches 3. The portions 4 may also be weakened by 75 the punching operation, so that they may be easily and readily removed without the use of any tool.

The blades in strip form are then tempered by being immersed in melted lead or other suitable metal, or in the desired manner. After this step, the blades, still in strip 80 form are polished on suitable buffers.

Next, the strip of blades are ground and honed on suitable grinders, and then stropped on any type of stroppers desired, 85 after which they are ready for the final step in the process.

The final step consists in the breaking off of the completed safety razor blades, by one or two operations, either by dies, stamp 90 presses or by hand.

It will be apparent that in each step in my process, no special machinery will be required, and that the blades may be manufactured in large numbers at one time, they 95 being formed in strip form, and that all of the blades will be uniform throughout in every detail, since they are all formed from the same width strip or ribbon of steel.

Thus, I have provided and invented a new 100 and improved process of manufacturing safety razor blades, which will be of great benefit to those who manufacture safety razor blades, as my process is highly efficient, and the cost of manufacturing the blades 105 will be the minimum amount.

Many minor changes in detail of manufacture may be resorted to without departure from the spirit of the invention.

Having thus described my invention what 110

I claim as new and desire to secure by Letters Patent of the United States is:

1. The process of manufacturing safety razor blades comprising the running of a strip or ribbon of steel through a punch to form central openings and adjoining end positioning seats or notches, tempering in a suitable bath, polishing on buffers, and finally sharpening on suitable hones.
- 10 2. The process of manufacturing safety razor blades comprising the running of a strip or ribbon of steel through a punch to form central openings and adjoining end positioning seats and oppositely disposed weakened areas, tempering in a suitable bath, polishing on buffers, and finally sharpening on suitable hones.
- 15 3. The process of manufacturing safety razor blades comprising the running of a

strip or ribbon of steel through a punch to 20 form central openings and adjoining end positioning seats or notches and oppositely disposed weakened areas, tempering in a suitable bath, polishing on buffers, sharpening on suitable hones, and finally breaking 25 off the completed blades from the strip.

4. The process of manufacturing safety razor blades comprising the running of a strip or ribbon of steel through a punch to form central openings and adjoining positioning seats or notches and oppositely disposed wedge-shaped notches therein, tempering in a suitable bath, polishing on buffers, sharpening on suitable hones, and finally breaking off the completed blades from the 30 strip without the use of any kind of tools.

In testimony whereof I affix my signature.
JAMES F. BARRY.
